Fig. 3.

Fig. 4.

Diagram illustrating a cross-section of a double-decker bus, specifically the rear section. The diagram shows two main sections: a lower section with a central vertical support and an upper section. Various components are labeled with numbers: 17, 33, 3831, 35, 6, 8, 32, 13, 38, 35, 7, 5, 8, 13, and 16. At the top of the diagram, there are handwritten numbers: 29, 7, 60, 9, 69, and 11. The diagram is rendered in black and white, with some areas shaded to indicate different parts of the bus structure.

Specification of Letters Patent. Patented Nov. 23, 1920.

Application filed March 22, 1920. Serial No. 367,709.

To all whom it may concern:

Be it known that I, PETER G. STEVENSON, a subject of the King of Great Britain and a resident of the city of Philadelphia, county 5 of Philadelphia, State of Pennsylvania, have invented certain new and useful Improvements in Railway-Crossings, of which the following is a specification, reference being had to the accompanying drawings.

10 My invention relates to a new and useful device adapted to be used at railway crossings where the tracks cross at an angle to each other.

15 Among the objects of my invention is to provide a new and useful device adapted to be connected to the crossing rails of the track whereby the noise and the jarring action usually accompanying the travel of a car at the crossing will be substantially 20 eliminated or avoided.

Another object of my invention is to provide a device which will operate and maintain the wheels of the car at the same level as the rail surface when passing across the 25 flange groove of a transverse rail.

Another object of my invention is to provide such device with means operable by the car itself and to act as an evener device.

Other objects of my invention will more 30 fully appear in the following description and upon the accompanying drawing.

Referring to the drawing;

Figure 1 is a top plan view of the device;

Fig. 2 is a bottom view with parts shown 35 in section;

Fig. 3 is a plan view with parts shown in section of the device adapted for use with tracks that cross each other at a different angle than 90°;

40 Fig. 4 is a fragmentary transverse section with a device showing the relative position of the evener members in respect to track and the car wheels, and,

Fig. 5 is a similar view at right angles to 45 Fig. 4.

Referring more particularly to the drawing wherein the same reference characters are used to designate the corresponding parts in the several views I have shown the 50 device mentioned above comprising a casting provided with a top plate 1, side walls 2 and center legs 3 integrally cast with each other. The casting is of general rectangular or square shape with the leg portions 3

suitably spaced from each other in two directions to provide therebetween channels or spaces within which may move and be guided thereby the transversely disposed evener members 4 and 5. These members comprise base pieces 4' and 5' and wheel 60 flange contacting members 6 and 7 adapted to slide longitudinally thereof in the dovetail grooves 32 and 33 respectively provided in the upper edges of the members 4' and 5'. The members 4' and 5' are also provided 65 with transverse slots 6' and 7' whereby said members 4' and 5' are adapted to fit together telescopically or the like and the slots 6' and 7' are of the proper length to permit 70 a certain amount of relative movement between the evener members 4 and 5.

Between the side wall 2 and the member 3 on each side of the casting is located a lever 8 mounted upon a pivot pin 9, supported at one end thereof in a bearing 10 in 75 a side wall 2 and at the other end thereof in a bearing 11 in a center member 3. The bearing members 10 and 11 may be of composition to provide a durable bearing for the pivot pin 9. The opposite ends of the lever 80 8 project into apertures 12 and 13 respectively in the evener members 4 and 5 whereby movement may be imparted to the latter by the ends of said levers. When an end 14 of the lever 8 moves upwardly and the other 85 end 15 moves downwardly the evener member 4 will be raised by the end 14 and the evener member 5 will be lowered by the end 15.

The casting is located in a recess provided 90 in the road bed between the ends of the alined rails or sections 16 and 17 which are cut to provide a suitable space therebetween for the inclusion of the device forming the subject matter of my invention. The casting as shown in Fig. 2 is of substantially 95 square formation and is adapted to be placed between the ends of the rails 16 and 17 with a diagonal of the casting in alinement with said rails and with another diagonal at right 100 angles to the first in alinement with the transverse rails 18 and 19. To the outer surface of the side walls 2 of the casting are secured channel iron members 20 suitably bent at the ends thereof to be secured to the web portion 21 of the rails, by means of suitable bolts 22, with the intermediate portion 23 of the channels 20 in contact with the 105

outer surface of the side wall 2 and opposite the pivot pin 9, maintaining the latter in position or from longitudinal displacement.

5 The top plate 1, cast integrally with the members 2 and 3, spans the space between the ends of the transverse rails and is provided with traction portions 24 and 25 in exact alignment with the traction surface of 10 the rails to form a continuing supporting surface for the tire of the car wheel. Adjacent to said surfaces 24 and 25 are provided slots 26 and 27 respectively in direct alignment with the flange-grooves of the corresponding track rails so that the wheel of the car will ride from the track across the plate 1 with the latter acting as an extension of the rail. Within the slots 26 and 27 are disposed the evener members 6 and 7 with the 15 top surfaces thereof provided with a horizontal portion 28 and an inclined portion 29 adapted to be engaged with the flange of the car wheel traveling in the direction thereof but with the flat portion 28 thereof adapted to be contacted by the tire 30 of the car wheel when traveling transversely thereof. The portion 28 when in its uppermost position is upon the same level as the surfaces 24 and 25 so that the wheel tire in 20 crossing from one section thereof to the other will ride upon the surface 28 without the usual dropping of the wheel into the groove of the cross rail, making a noise and unduly vibrating the car, the flange of the wheel operating upon the other evener member to 25 maintain it in lowered position.

To accomplish the above result the central sections 3 are provided with downwardly converging inclined slots 34 and 35 and the 30 flange contacting members 6 and 7 provided on each side thereof with rigid or integral projections 36 and 37 adapted to slide in slots 34 and projections 38 and 39 adapted to slide in the slots 35. As a member 6 or 7 is forced downwardly, the riding of the projections 36 and 37 or 38 and 39 in the slots 34 or 35 will cause a simultaneous relative longitudinal movement of the member 6 or 7 with respect to the members 4' or 5' along 35 the dove-tail grooves 32 or 33 thereof. The downward movement of the members 4' or 5' will cause the other member 7 or 6, by reason of the dove-tail connection therebetween to draw the same downwardly, at the same time causing the lateral projections 38 and 39 or 36 and 37, as the case may be, to slide in the slots 35 or 34 respectively thereby causing the members 7 or 6 to approach each other. A reverse movement will cause the same to 40 separate when the flange of a wheel travels in a cross-direction and operates to lower the transverse evener member.

The inner ends of the members 6 and 7 are so cut with the bevels 40 and 41 so that as 45 members 6 are approaching each other the

members 7 are receding and the bevels permit the latter to clear the former as fast as the former advance or approach each other. In Fig. 1 the members 6 are shown in lowered position with the ends thereof in contact at 70 the center of the device whereby the flange of the car wheel traveling in the direction of the length of the members 6 will maintain contact, and the members 7 are in uppermost position whereby the surfaces 28 are 75 on the same level as the surfaces 24 for continuous smooth passage of the tire of the car wheel.

In operation when a car arrives at the crossing the flange of the car wheel will contact with the inclined or curved surface 29 of the evener member disposed in the slot corresponding to and in alignment with the groove of the track upon which the wheel is traveling so that the flange 31 of the wheel 85 will depress said evener member, as for example, as is shown in Fig. 5. Said member will by its downward movement force the ends of the levers 8 projecting in the apertures thereof downwardly thereby causing 90 the opposite ends of said levers to move upwardly. Inasmuch as the opposite ends of the levers are projecting into apertures in the transverse evener member the latter will be caused to rise in the transverse slot of the 95 device so as to bring the surface 28 thereof into horizontal level even with the surface upon which the car wheel tire is traveling so that as the wheel crosses the raised evener member on the surface 28 it will do so 100 smoothly without dropping into the groove of the transverse track, the flange 31 at the same time continuing to ride on the first mentioned evener member holding it in its lowered position so that the raised evener 105 member will be maintained in its uppermost position.

In Fig. 3 I have shown a device adapted for use with rails that are disposed at a different angle than 90°. The construction, 110 however, is similar to that above described with the exception that the ends of the levers 8' instead of abutting each other in the apertures 12' and 13' of the evener members 4" and 5" are disposed in overlapped 115 adjacent relation. This construction is followed in order that the levers may be of equal size and of equal lever effect, the moments of force being equal about each pivot pin 9' as well as that the movement of the 120 ends of said levers will also be equal whereby the evener members may be caused to move with a balanced action at both ends thereof and to an equal extent, or in other words, when one of the evener members is 125 lowered the other will be raised to a corresponding equal extent and vice versa. It will be observed that the radial distances from the axis of the pivot pin 9' to the effective point of contact between the end of 130

the lever 8' and the evener member are equal for all levers shown. The operation of this device is the same as that described above in connection with Figs. 1, 2, 4 and 5.

5 While I have herein described and shown upon the drawing two embodiments of my invention it is to be understood, however, that my invention is not to be limited to the particular details shown and described 10 but that the same comprehends other devices and constructions that do not depart from the spirit of my invention and the scope of the appended claims.

Having thus described my invention what 15 I claim as new and desire to protect by Letters Patent of the United States is:

1. In a railway track crossing, the combination of a member connected to the ends of the transverse rails and provided with 20 transverse slots over which wheels of a car are adapted to travel, evener members in the slots of said member, levers pivotally mounted between and connected to the ends of said evener members whereby the downward movement of one of said evener members will move said levers and cause an upward movement of the other evener members in said slots, and bring the upper surface of the upwardly moved evener member 25 30 in coincidence with the top surface of the tracks upon which a car wheel is traveling.

2. In a railway crossing, the combination

of a member connected to the ends of the transverse rails and provided with transverse slots in which the flanges of car wheels 35 are adapted to travel, evener members in said slots, levers pivotally mounted between and connected to the ends of said evener members, whereby the engagement of said flanges with one of said evener members 40 will depress the same and move said levers causing the other evener member to move simultaneously upwardly into the plane of the top surface of the tracks upon which the car wheel is traveling.

3. In a railway crossing, the combination of a member connected to the ends of the transverse rails and provided with transverse slots in which the flanges of car wheels are adapted to travel, evener members in 50 said slots, levers pivotally mounted between and connected to the ends of said evener members, whereby the engagement of said flanges with one of said evener members will depress the same and move said levers 55 to simultaneously elevate the other evener member into the plane of the top surface of said rails where it is rigidly retained during said engagement of said flanges with said depressed evener member.

In witness whereof, I have hereunto set my hand this 20 day of March, 1920.

PETER G. STEVENSON.
